CIRCUMFERENCE AND CENTER POINT
MARKER

Hie N. Oprescu, Providence, R. I.

Application May 24, 1946, Serial No. 672,107

1 Claim. (Cl. 33—191)

1

This invention relates to a center point cylindrical punch, and more particularly to such a device adapted for scribing circles and indicating the center points thereof in relation to bores of predetermined diameters.

A primary object of this invention is the provision of an improved device including a plurality of interchangeable cylindrical punches, each provided with a cutting edge and each adapted for a bore of a given diameter, each of which is provided with a centrally positioned aperture of identical diameter adapted to accommodate a center punch.

A further object of the invention is the provision of a tool of this character adapted to simplify the work of tool makers, machinists and others in accurately determining the outline diameter of and the exact center of circles to be drilled or otherwise machined.

Other objects of the invention will in part be obvious and in part be pointed out as the description of the invention proceeds, and shown in the accompanying drawings, wherein there is disclosed a preferred embodiment of this inventive concept.

In the drawings:

Figure 1 is a vertical sectional view taken substantially through the center line of one form of cylindrical punch embodying features of the instant invention disclosing the center punch in association therewith.

Figure 2 is a view similar to Figure 1, but showing a different diameter of cylindrical punch and the center punch removed.

Figure 3 is a side elevational view of one form of cylindrical punch having the center punch associated therewith, shown in association with a piece of material to be marked through a bore of a diameter in conformity to the diameter of the cylindrical punch, the material in which the bore is formed being disclosed in section.

Similar reference characters refer to similar parts throughout the several views of the drawings.

Having reference now to Figure 1, there is generally indicated at 10 a cylindrical punch of any desired diameter, the lower portion of which is recessed, as at 11, the edges being beveled, as at 12, to provide a cutting edge 13 for scribing the exterior diameter of a circle of the exact size of the punch. The punch 10 is provided at its center with an accurately aligned bore 14 extending from the upper extremity thereof into the recessed portion 11, within which is adapted to fit an elongated center punch 15 provided with

2

a point 16 adapted to extend a slight distance below the plane of the cutting edge 13. The upper extremity of the pin 15 carries an enlarged head 17 of relatively heavy material, adapted to overlie the corresponding end of an associated cylindrical punch 10 and transmit the force of a hammer blow thereon to the cylindrical punch and center punch simultaneously.

Figure 2 discloses a similar cylindrical punch 10' provided with a recess 11' beveled, as at 12', to form a cutting edge 13', and being provided with an internal bore 14'. It is to be noted that the punch 10' is substantially identical to the punch 10 with the exception of its external diameter. The diameter of the internal bore 14' is substantially identical to the bore 14, and the length of punch 10' is substantially the same as that of punch 10 so that either the punch 10 or the punch 10' will accommodate the center punch 15.

Obviously, numerous cylindrical punches similar to the above two described may be made in a variety of diameters, and are adapted to be accommodated in bores 18 formed in stock 19 of any suitable type, as disclosed in Figure 3, for the purpose of scribing circles with the edges 13 and marking the centers thereof with the point 16 on any suitable material 20 to be worked.

From the foregoing the operation of the device should be readily understandable. When it is desired to mark and center a circle in any desired piece of material 20 through a bore 18, a selected cylindrical punch 10 is first inserted in the bore, whereupon the center punch 15 with its centering point 16 is inserted in the associated bore 14 to its full length, the point 16 extending a slight distance below the plane of the cutting edge 13. A relatively sharp blow with a hammer or similar device on the head 17 will cause the cutting edge 13 to scribe the external diameter of the circle to be cut, and will simultaneously through the point 16 mark the exact center of the circle.

From the foregoing it will now be seen that there is herein provided a device which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

A circumference and center punch assembly comprising a cylindrical punch having a central bore therethrough and a beveled peripheral flange at one end having a cutting edge conforming to the outer diameter of said punch, an elongated center punch of a length slightly greater than the length of said cylindrical punch removably positioned in the bore of said cylindrical punch and having a pointed end substantially in the plane of the cutting edge of said cylindrical punch end flange, and a head secured on the end of said center punch opposite the pointed end thereof and overlying the corresponding end of said cylindrical punch to transmit the force of a hammer blow on said head to

said cylindrical punch and said center punch simultaneously.

ILIE N. OPRESCU.
